UNITED STATES PATENT OFFICE

FREDERICK L. FULLER, OF ILION, NEW YORK, ASSIGNOR TO THE NATIONAL CASH REGISTER COMPANY, OF DAYTON, OHIO, A CORPORATION OF MARYLAND

CASH REGISTER

Original application filed May 23, 1919, Serial No. 299,112. Divided and this application filed March 7, 1927. Serial No. 173,391.

This is a division of the application for Letters Patent of the United States of Frederick L. Fuller, Serial No. 299,112, filed May 23, 1919.

The objects of the present improvement are to provide:

A novel release mechanism, controlled by various manipulative devices, so constructed that a certain predetermined number of manipulative devices must be operated before the release of the machine is effected.

To combine with the release mechanism, above mentioned, a device actuated by the total lever so that, after movement of the total lever, to control the machine to perform a total or sub-total operation, a manipulative device in any bank selected by the total lever may be operated to effect the release of the machine, the manipulative devices in the other banks being locked against operation.

An improved form of interlocking mechanism controlled by the total lever and co-operating with the zero stop pawls of the various control banks of manipulative devices.

With these and incidental objects in view, the invention consists of certain novel features of construction and combinations of parts, the essential elements of which are set forth in appended claims, and a preferred form or embodiment of which is hereinafter described with reference to the drawings which accompany and form part of this specification.

Of said drawings:

Fig. 1 is a diagrammatic view of the three banks of control keys and the total lever.

Fig. 2 shows the operating connections from the motor to the main cam shaft, and also the connections to the machine release mechanism.

Fig. 3 shows the connections from the operating handle to the main cam shaft, the mechanism for operating the machine release mechanism, and the connections for permitting two rotations of the cam shaft during total operations.

Fig. 4 shows the connections from the total lever to the machine release mechanism and a

portion of the interlocking device between the total lever and the control keys.

Fig. 5 is a detail plan view, partly in section, of the machine release mechanism.

Fig. 6 is a view in left elevation, partly broken away, of the clerks' control key bank.

Fig. 7 is a perspective view of the interlocking mechanism between the control banks, and between said control banks and the total lever.

Fig. 8 is a detail fragmentary view of the releasing bar and arm showing their relation to the clerks' keys.

General description

Since this is a divisional application only so much of the mechanism of the parent case is shown as is necessary to fully illustrate the interlocking mechanism comprising this invention.

Therefore, the amount keys, the differential mechanisms, the totalizers, the indicators and the printing mechanism are not shown and will not be described in this case. Since the interlocking mechanism applies only to the banks of control keys and the total lever, such keys only are illustrated herein. In the preferred form these keys bear characters adapted more especially for use in markets and such analogous lines of businesses.

However, applicant does not wish to limit his invention to machines which can be used in markets only, because the characters on the keys may be readily changed to fit the requirement of many lines of business.

Described in general terms, this invention includes an interlocking mechanism arranged to cooperate with the three banks of control keys and the total lever in such a manner as to always require, during adding operations, the depression of a key in each bank, and at the same time prevent an operation of the total lever during adding operations. It also compels the total lever to be in the "add" position prior to the depression of any of the keys for an adding operation.

The interlocking mechanism also cooperates with the control keys and total lever during total and sub-total operations in such a manner that, when the total lever is moved

55

60

65

70

75

80

85

95

100

to the "transaction" position, only a key in the transaction bank can be depressed, the keys in the other banks being locked out. Likewise, when the total lever is moved to the "department" position, only a key in the department bank can be depressed, the keys in the other two banks being locked out. When the total lever is moved to the "clerks'" position, then only a key in the clerks' bank may be depressed, the keys in the other two banks being locked out.

The interlocking mechanism is so interrelated with the machine releasing mechanism that all of the above functions are accomplished, so that there can be no mis-registration on the part of the operator when a sale is recorded. The mechanism also prevents a mis-operation by the proprietor when he either reads or resets the various totalizers in the machine to which this invention is applied.

The specific manner of accomplishing these results will appear in the detail description to follow.

25   *Operating mechanism*

The motor mechanism convenient to use in connection with the present invention is of a well known type, and described in United States Letters Patent No. 1,144,418, granted to Charles F. Kettering and William A. Chryst on June 29, 1915. For a detailed description of the same, reference may be had to this patent. The only part of the motor mechanism necessary to illustrate in this case is shown in Fig. 2. A worm gear 30, which forms part of a motor clutch device, is loosely mounted on a stud 31 carried by the machine side frame. This worm gear 30 is rotated by a worm 32 on the armature shaft of the motor (not shown). The motor clutch has three locking disks, only one of which, 33, is shown. Each disk has a stop plate 34 engaged by the nose of a locking lever 35 pivoted on a stud 36 on the machine frame.

45   The locking disks 33 perform certain functions in connection with the release and operation of the motor clutch and the closing of the electric circuit, as is fully illustrated and described in the Kettering and Chryst patent above mentioned. The upper end of the lever 35 carries a roller 37 normally resting on a curved surface 38 of an arm 39 fast upon a shaft 40. When the arm 39 is rocked clockwise (Fig. 2) to release the machine, as will be hereinafter described, the lever 35 is rocked clockwise, by a spring 45, and disengaged from the stop plates 34, whereupon the disks, and parts operated thereby, are moved, by 55   spring action, to effect the connection of the motor clutch and the closing of the circuit through the motor as described in the Kettering and Chryst patent. The lever 35 is limited in its clockwise movement by a stud 46 60   on the machine frame.

A gear 47 is secured to the motor clutch and meshes with an intermediate gear 48 meshing with a gear 49 fast on the main cam shaft 50.

Through this gearing and the motor clutch, the motor (not shown) drives the shaft 50 one complete rotation for each adding operation of the machine.

To restore the locking lever 35 to normal position near the end of the operation of the machine, a link 55 is pivoted to said lever. The link 55 is guided in its movements by its slot 56 embracing a stud 57 on the machine frame. The gear 48 carries a stud 58 which, near the end of the operation of the machine, contacts the lower surface 59 of the link 55, thus raising the link and thereby moving the locking lever 35 to its normal locking position.

As will be later described, the arm 39 is rocked to its normal position just before the stud 58 passes off the surface 59, in order to retain the lever 35 in its normal position.

Since, in some cases, it may be desirable to operate the machine by hand instead of by motor, a manual operating mechanism is provided in addition to the motor driving mechanism.

A hand crank (not shown), carrying a gear 65, (Fig. 3) is mounted upon a stud 66 carried by the machine side frame, and may be held against longitudinal movement on the stud 66 in any desired manner.

The gear 65 meshes with a gear 67 rotatably mounted on a stud 68 in the machine frame. This gear 67, in turn, meshes with a gear 69 fast on the cam shaft 50. The ratio of the gears 65, 67 and 69 is such that two rotations of the gear 65 cause a half rotation of the gear 67 and a complete rotation of the gear 69. The functions of the arm 39 and the lever 35 are the same as described in connection with the motor drive. The only difference in the two driving means resides in the fact that in one case the shaft 50 is rotated by a motor, and in the other case by a hand operated crank.

Keyboard

That part of the keyboard shown in this case comprises a bank of clerks' keys 75 (Fig. 1), a bank of department keys 76, a bank of transaction keys 77 and a total lever 78. The construction of the department and transaction key banks is very similar to that shown and described in a patent granted to the applicant, No. 1,242,170, on October 9, 1917, hence a very brief description will suffice here.

In this case, as in the parent case, the clerks' keys are in reality true keys, since they are removable and, when put in the machine, are inserted in a lock barrel 80 (Fig. 6) carried by a frame 81 superimposed on a regular key frame 82, mounted on rods 83. In the present instance, only four clerks' keys are shown, but, as is perfectly

clear from the diagrammatic view in Fig. 1, nine may be used. As this construction is fully illustrated and described in the parent case, it will be sufficient here to say that the clerks' keys cooperate with key stems 84 mounted in the usual manner in the key frame 82.

The key stems 84 cooperate with studs 85 on a flexible detent 86 carried by arms 87 and 88 pivoted in the key frame 82. When a key stem 84 is depressed by a key 75, the detent 86 is first moved downwardly until the shoulder 89 is beneath the stud 85, after which said detent is moved upwardly and the flat portion of the stud 85 engages the shoulder 89, thus locking the key in depressed position and holding the detent in its moved position. The arm 88 engages a pin 95 on a zero stop pawl 96, pivoted in the key frame and held in normal position by a spring 97. The key stems 84 also carry pins 98 which cooperate with slots 99 in a releasing bar 100 (Fig. 8), pivoted at its upper end to an arm 101 mounted in the key frame, and at its lower end to an arm (not shown). The arm 101 has a pin 102 embraced by a slotted arm 103 (Figs. 5 and 6), integral with a sleeve 104 loose upon a shaft 105. Also integral with the sleeve 104 is an arm 106, the free end of which normally rests in front of one of two L-shaped arms 107, integral with a sleeve 108 loose on the machine release shaft 40. The sleeve 108 has a projection 109 embraced by a slotted arm 110 fast on the shaft 40.

By reason of this construction, rotation of the shaft 40 will, through the arm 110 and projection 109, rotate the sleeve 108, and movement of the sleeve longitudinally of the shaft is permitted.

The construction and elements of the department key bank are the same as the clerks' bank, except in the department bank the keys 76 are not mounted in a superimposed frame, but are integral with the key stems 84. This key bank has a flexible detent 86 (Fig. 5) which cooperates with a zero stop pawl 113 (Fig. 7); a releasing bar 100 (Fig. 5); an arm 101 and a pin 102 cooperating with an arm 103 on a sleeve 104. This sleeve 104 has integral therewith an arm 111, the free end of which lies in front of an L-shaped arm 112 integral with the sleeve 108.

The transaction bank is like the department bank, except that it has, in this case, only five keys. A greater number up to nine may be used in this bank. This bank of keys also has a detent 86 cooperating with a zero stop pawl 114 (Fig. 7) a releasing bar 100 (Fig. 5); an arm 101 and a pin 102 cooperating with an arm 103 on a sleeve 104. This sleeve 104 has integral therewith an arm 115, the free end of which lies in front of an L-shaped arm 116 integral with the sleeve 108.

The three arms 106, 111 and 115, associated

with the clerks' key bank, department key bank and transaction key bank, respectively, and which abut the arms 107, 112 and 116, all integral with the sleeve 108 (Fig. 5), prevent counter-clockwise movement of said sleeve 70 (Fig. 6), the engagement of any one of these arms serving to prevent such counter-clockwise movement. Consequently, in the normal condition of the machine, when the total lever 78 is in the position shown in Figs. 1 75 and 4, it is necessary to rock all three arms 106, 111 and 115 out of the paths of the three integral arms on the sleeve 108 in order to permit counter-clockwise movement of said sleeves. Therefore, in order to move said arms a key must be depressed in the transaction, departmental and clerks' key banks. 80

The sleeve 108, as previously described, by the projection 109 and arm 110 pinned on the shaft 40, is rocked with said shaft, the latter 85 receiving its movement from a compression spring 119 (Fig. 3) mounted in a slot 120 in a link 121. Said spring is also connected to a stud 122 on an arm 123 fast on the shaft 40. This spring 119 normally tends to rock the arm 123 clockwise (Fig. 3), which movement, however, is normally prevented, as previously described. When the shaft 40 is permitted a clockwise movement (Fig. 3) by depression of a key in the transaction, departmental and clerks' banks, the arm 35 (Fig. 2) is rocked clockwise, thereby effecting the coupling and starting of the motor for driving the cam shaft 50, as previously described, or permitting a manual operation by use of the crank 90 handle (not shown).

It is not necessary to depress the keys in the control banks simultaneously, or in any particular sequence, because as each key is depressed it is held in depressed position by its flexible detent 86 and locked in this position 105 after the machine is released.

To effect the release of the keys, near the end of the operation of the machine, the link 121 (Fig. 3) is provided with a slot 124, one 110 section of which normally embraces a pin 125 on a lever 126 pivoted on a stud 127. The lever 126 carries a roller 128 engaging a cam-race 129 in the gear 67. As previously stated, this gear is given a half rotation at each adding operation of the machine. Consequently, this race 129 has two nodes 130 so located that near the end of the adding operation the lever 126 is rocked clockwise to lower the link 121. As the link 121 is lowered, the upper end of the slot 120 engages the stud 122 whereby the shaft 40 is rocked counter-clockwise (Fig. 3) past normal position, and then permitted to rock clockwise to its normal position. The shaft 40 in its counter-clockwise movement releases all of the amount keys depressed in the machine to which this invention is applied. 115

When the shaft 40 is rocked as above described, the arm 39 (Fig. 2) is moved to its 120 125 130

normal position, the lever 35 having been restored to normal locking position by the link 55 and stud 58 before the arm 39 is moved to its normal position, as has been previously described.

The above described movement of the shaft 40 past its normal position is employed to effect the release of the depressed transaction, departmental and clerks' keys. As the shaft 40 is rocked counter-clockwise (Fig. 3), or clockwise (Fig. 6), the arms 107, 112 and 116 are also rocked from their positions beneath the arms 106, 111 and 115. As the shaft 40 rocks past its normal position, an arm 141 fast on the shaft 40 and projections 142 and 143 on the sleeve 108 engage extensions 144 (Fig. 6) on the flexible detents 86 of the three control banks and force them downwardly. Since the releasing bars 100 are free to move upwardly after the removal of the arms 106, 111 and 115, this movement of the arm 141 and projections 142 and 143 permits the springs (not shown) beneath the keys to restore the depressed keys in the transaction, departmental and clerks' banks to un-depressed position.

To prevent the operator from retaining the depressed keys in the transaction, departmental and clerks' banks in depressed positions until the end of one complete rotation of the machine, and thereby causing an immediate second operation of the machine, arms 145 (Figs. 5 and 6), pivoted on the shaft 105, cooperate with each of the L-shaped arms 107, 112 and 116. When the machine is released, the arms 107, 112 and 116 move between the arms 106, 111 and 115 and the arms 145. When the shaft 40 is rotated clockwise (Fig. 6) past normal position near the end of the operation of the machine, the arms 107, 112 and 116 are carried rearwardly past normal positions, so that if the operator retains any of the keys 75, 76 or 77 in depressed positions, a spring 146 (Fig. 6) connecting arms 145 to arms 106, 111 and 115, will rock the arms 145 and a shoulder 147 thereon will engage the L-shaped arms 107, 112 and 116, thus preventing counter-clockwise rocking of the sleeve 108 and shaft 40 to release the machine. When the operator finally removes his fingers from the depressed keys 75, 76 and 77, the arms 106, 111 and 115 will be lowered in front of the L-shaped arms 107, 112 and 116, and as the lower edges of the former arms engage the upper edges of the arms 145, these arms at the same time are moved so that the shoulders 147 are removed from the arms 107, 112 and 116, thus permitting these arms to rock a slight distance counter-clockwise (Fig. 3) to their normal positions, abutting the arms 106, 111 and 115.

This mechanism just described applies, not only to a case where a key in all three banks may be held depressed, but to a case where a key in only one bank may be held depressed

during a total operation. It is just as effective during total operations as during adding operations.

The total lever 78 is pivoted on a shaft 149 (Fig. 4) and is movable in a slot 150 (Fig. 1). If the lever is moved above its central or "add" position, it controls the machine for sub-total or reading operations, and when moved below its "add" position it controls the machine for grand total or reset operations. When the total lever 78 is in position to control the machine for a sub-total or a grand total operation, only one key in one of the banks 75, 76 and 77 is depressed, because at such a time only one individual totalizer is to be selected and engaged with the differential mechanism, as has been fully illustrated and described in the parent application.

Since only one key is depressed, mechanism is provided whereby it alone may release the machine, although in adding operations, as previously described, the depression of one key in each bank 75, 76 and 77 is absolutely necessary.

Integral with the total lever 78 is a rack 155 (Fig. 4) meshing with a gear 156 loose on the shaft 105. Secured to the gear 156 is a drum cam 157 (Figs. 4 and 5) having a race 158 which receives a roller 159 carried by a sleeve 160 loosely mounted on a reduced portion of the end of the sleeve 108. The sleeve 160 is held in position by a collar 161. An arm 165, secured to the sleeve 160 and bifurcated to fit the shaft 105, prevents rotation of the sleeve 160, and at the same time permits oscillation of the sleeve 108 to release the machine, as previously described.

When the total lever 78 is moved, either up or down, in the slot 150 from its central or adding position, it will, through the rack 155, gear 156, cam 157, roller 159 and sleeve 160, move the sleeve 108, as viewed in Fig. 5, up one step for the transaction position. If the lever 78 is moved past this position to the department position, the sleeve 108 will then be moved down two steps, and if said lever is moved past the department position into the clerks' position, the sleeve 108 will be moved down another step. This sliding of the sleeve 108 will, as the total lever is moved each step in the directions mentioned, move the L-shaped arms 107, 112 and 116 out of contact with two of the three arms 106, 111 and 115, so that only one of the latter arms will engage one of the former L-shaped arms. Therefore, the movement of only one of the arms 106, 111 or 115 is necessary to release the machine during a total or sub-total operation. The arm 106, 111 or 115 which abuts its associated L-shaped arm and prevents the release of the machine is the arm associated with the key bank selected by the total lever to take a sub-total or total of the individual totalizer which may be selected by the de-

70

80

90

95

100

105

110

115

120

125

130

pression of a key in this bank, as is fully described in the parent application.

Summing up the movements of the parts under the control of the total lever 78, said lever, by its movement into either of the transaction positions, causes the clerks' arm 106 and department arm 111 to be moved out of the paths of their associated L-shaped arms 107, 112 respectively, but the arm 115 10 remains in cooperative relation with its associated L-shaped arm 116. When the lever 78 is moved into either of the department positions, the clerks' arm 106 and transaction arm 115 are moved out of the paths of their 15 associated arms 107, 116 respectively, and the department arm 111 remains in cooperative relation with its associated arm 112. When the total lever 78 is moved into either of the clerks' positions, the department arm 111 20 and transaction arm 115 are moved out of the paths of their associated L-shaped arms 112, 116 respectively, and the clerks' arm 106 remains in cooperative relation with its associated arm 107. Therefore, it is clear that 25 when the machine is set for total taking operations, two of the three arms 106, 111 and 115, are moved into ineffective positions, relative to their associated L-shaped arms 107, 112 and 116, depending upon the position 30 in which the total lever is set, thus necessitating the depression of a key in one bank only to release the machine, that bank being the one corresponding to the position in which the total lever is set.

35 In addition to rendering any of the banks of keys 75, 76 or 77 singly a release bank for the machine by movement of the total lever, an interlocking mechanism is controlled, by the movement of said lever, to lock the keys 40 in the other two of these banks not selected, so that they can not be depressed during the total or sub-total operation of the machine.

This mechanism includes a segment 170 (Fig. 4) secured to the total lever 78. Meshing with the segment 170 is a segment 171 45 mounted on a shaft 172. Secured to the segment 171 is a bar 173 (Fig. 7) also attached to disks 174, 175 and 176 loosely mounted on nested sleeves (not shown) on the shaft 172. 50 Each of the disks 174, 175 and 176 has a laterally extending flange 177 provided with one or more notches 178. These flanges are 55 located directly beneath downwardly extending tails 179 on the zero stop pawls 96, 113 and 114 associated with the clerks', department and transaction banks, respectively.

When the total lever 78 is in its adding position, the disks 174, 175 and 176 are in the positions shown in Fig. 7, in which the 60 tails 179 of all of the zero stop pawls are free to move downwardly within the notches 178 and any of the keys 75, 76 or 77 can be depressed, the depression of the keys rocking their associated zero stop pawls 96, 113 or 65 114, as the case may be, counter-clockwise.

These are the positions assumed during adding operations. When, however, the total lever 78 is moved either up or down to select any one of the banks of keys 75, 76 or 77 for a sub-total or total operation, the segments 70 170 and 171 are moved a distance sufficient to position the disks 174, 175 and 176, so that only the zero stop pawl 96, 113 or 114 associated with the selected bank can be moved downwardly through the slot 178 in the lateral flange 179. When the total lever has been so moved, two of the disks will be positioned so that the unbroken sections of the flanges 177 rest beneath the tails 179, thereby preventing any movement of their pawls and 80 consequently preventing depression of the associated keys.

Let it be assumed that the total lever 78 is moved upwardly one step from the "add" position. The lever 78, by this one step of movement positions the unbroken sections of the flanges 177 (Fig. 7) on the disks 174 and 175 directly beneath the tails 179 on the zero stop pawls 96 and 113. The notch 178 of the disk 176, because of its length, will still register 90 with the tail 179 of the pawl 114, and since this pawl is the one associated with the transaction bank of keys 77, any key in this bank may be depressed, but the keys 75 or 76 can not be depressed because the unbroken 95 sections of the flanges 177 on the disks 174 and 175 are in the paths of the pawls 96 and 113.

When the total lever is moved out of adding positions, preparatory to taking a total or sub-total, all of the amount keys are locked against depression, as is fully described in the parent application.

Means is also provided to prevent release of the machine, unless the total lever 78 has 105 been moved to its exact position to control the machine for adding, total or sub-total operations. Means is also provided for locking the total lever 78 in any of its adjusted positions during the operation of the machine.

The total lever 78 has a roller 185 (Fig. 4) which cooperates with the scalloped edge of a lever 186 fast to a sleeve 187 loose on a stud 188 on the machine frame. Also secured to the sleeve 187 is an arm 189 having a pin 190 110 embraced by an arm 191 pivoted on a stud 192 on the machine frame. A spring 193 stretched between the arm 191 and a lever 194, pivoted on the shaft 149, tends to rock the arm 191 counter-clockwise, which, through the arm 189, rocks the lever 186 clockwise so that its scalloped upper edge contacts the roller 185 on the total lever. The arm 191 has a lip 195 (Figs. 3 and 4) which cooperates with an arm 196 fast on the machine release shaft 40.

When the roller 185 is positioned within any of the depressions of the scalloped edge of the lever 186, the arm 191 will be so positioned that the lip 195 will be out of the path 130

of movement of the arm 196, and, consequently, when the sleeve 108 is released, through the depression of one of the keys 75, 76 or 77 during a total operation, or when the sleeve 5 108 is released through the depression of a key in all three banks during an adding operation, the shaft 40 will be free to move clockwise (Fig. 3) under the influence of its spring 120.

- 10 However, when the total lever is in any position, intermediate any of its positions of adjustment, the roller 185 is positioned on one of the high points of the scalloped edge of the lever 186, the lip 195 of the arm 191 will be 15 directly in the path of movement of the arm 196 on the shaft 40, and the shaft 40 cannot be moved and the machine cannot be released. This last described mechanism insures that the total lever be set in its correct position before 20 the machine can be released and the motor started.

After the machine has been released and begun its operation, the lower end of an arm 197, integral with the lever 194, is cammed 25 out of a notch 198 in a disk 199 fast on the cam shaft 50, and rides upon the periphery of the disk during the entire operation. The arm 197, as it is moved out of the notch 198, causes the lever 194 to be moved so that its 30 upper end rests beneath a flattened pin 200 on the lever 186. Therefore, during the operation of the machine the lever 186 cannot be moved downwardly, and the total lever is locked, the roller 185 being positively held in 35 one of the depressions of the scalloped edge of the lever 186, depending upon the position in which the total lever has been set. However, when the machine is in its home position and the arm 197 engages the notch 198, 40 the lever 194 is out of the path of movement of the pin 200 on the lever 186, thus permitting a movement of the total lever from adding to a total or sub-total position or from a total and sub-total to the adding position.

45 *Differential mechanism, totalizers, indicators and printing mechanism*

None of the mechanisms mentioned in the above heading are illustrated or described in 50 this divisional application, because it is not thought necessary to so do in order to fully illustrate and describe the interlocking invention.

Total and sub-total

55 In order to allow sufficient time for the selection and engagement of any desired totalizer with the actuating racks, when a total or sub-total is to be printed, the main cam shaft 50 is given two continuous rotations during all total and sub-total operations, instead of one, as is the case in adding operations. The mechanism for controlling the two rotations of the cam shaft is practically the same as that illustrated in the pre-

viously mentioned Fuller Patent. No. 1,242,170.

Since this mechanism is fully described in the last mentioned patent, and is also described in the parent application, only so much of the mechanism will be discussed as is necessary to show the cooperation of the interlocking mechanism and the driving mechanism during total operations.

During adding operations, the keys 75, 76 and 77 are permitted to rise to their normal positions just prior to the end of the operation of the cam shaft 50, and since in total operations this cam shaft makes two rotations, instead of one, it is necessary to prevent the release of the keys near the end of the first rotation and permit the release of the keys to take place only prior to the end of the second rotation of the cam shaft 50.

When the total lever 78 is moved either up or down out of its adding position, it moves mechanism (not shown herein but fully shown in the parent application), connected to a lever 201 (Fig. 3) pivoted to a link 202, which link carries a stud 203 entered in a slot 204 in the link 123. This link 202 carries pins 205, one on each side of a lug 206 on a slidable coupling bar 207 mounted in a groove (not shown) in the back side of a cam 208. This cam, in turn, is mounted in a recess in the gear 67. All of the details of this particular construction are illustrated and described in the parent case. The link 202 also carries a roller 209 which normally lies in a notch 210 in the cam 208. In adding operations, this cam 208 does not turn, but the gear 67 turns independently thereof. In total operations, however, the link 202 is moved toward the left, in the direction of its length (Fig. 3), by the total lever 78, and the pins 205 move the slidable coupling bar 207 to the left, so that the small end of said bar engages a recess 211 in the gear 67. Now, when the gear 67 is turned, the cam 208 will be turned with it. The movement of the link 202, by the total lever, also positions the roller 209 in the main part of the cam 208. During total operations, the gear 67 receives, as previously stated, one complete rotation, and therefore, the cam 208 will receive one complete rotation.

It will be remembered that it is the node 130 in the cam race in the gear 67 which moves the link 121 downwardly to restore the shaft 40 to its normal position and thus release the depressed keys. Since there are two of these nodes 130 in the gear 67, it is necessary that one of these should not be effective to move the link 121 downwardly at the end of the first half rotation of the gear 67. Therefore, the cam 208 is so timed that just before the first half rotation of the gear 67, the link 202 will be moved still farther to the left, in the direction of its length (Fig. 3), 130

thus rocking the link 121 clockwise with the stud 122 as the pivot. When the link 121 is in this position, the pin 125, during the first clockwise movement of the lever 126, moves idly in the longest portion 212 of the slot 124, thus preventing any downward movement of the link 121. Therefore, the shaft 40 is not moved at the end of the first half rotation of the gear 67, near the end of the first rotation 5 of the cam shaft 50.

10 However, before the end of the second rotation of the cam shaft 50, the cam 208 moves the link 202 to the right, thus rocking the link 121 counter-clockwise. Now, when the parts 15 are in these positions, and the second node 130 in the gear 67 operates the lever 126, the pin 125 strikes a shoulder 213 and moves the link 121 downwardly, whereby the upper end of its slot 120 will, through the arm 123, rock 20 the shaft 40 to cause a release of all depressed keys, so that they may be restored to their normal positions. Then when the total lever 25 78 is moved back to adding position the link 202 moves the link 121 to normal position and the pin 125 assumes the position shown in Fig. 3.

As the gear 49 receives two rotations during total and sub-total operations, the gear 48 also receives two rotations. Near the end of 30 the first rotation of the gear 48 the stud 58 thereon, by its contact with the surface 59 of the link 55, raises the link to the position shown in Fig. 2, thus rocking the locking lever from its released position to the position 35 indicated in Fig. 2. However, since the stud passes off the surface 59, the spring 45 again rocks the lever clockwise into its released position, because the arm 39 on the shaft 40 is not rocked from its released position back to the position shown in Fig. 2 near the end of 40 the first rotation of the shaft 50, due to the fact that the pin 125 (Fig. 3) operates idly in the longest portion 212 of the slot 124 in the link 121.

45 However, during the second rotation of the gear 48, the stud 58 again raises the link 55 and rocks the locking lever 35 to its normal position, and immediately thereafter the shaft 40 moves the arm 39 to its normal position, wherein the curved surface 38 thereof 50 cooperates with the pin 37 to maintain the lever 35 in its normal position, until again released by the depression of the proper keys for a subsequent operation of the machine.

55 The rocking of the shaft 40 counter-clockwise (Fig. 3) past its normal position during total and sub-total operations is to restore the depressed key 75, 76 or 77 to normal position to permit one of the arms 145 depending upon 60 which key 75, 76 or 77 has been depressed to be moved in front of its associated L-shaped arm 107, 112 or 116 (Figs. 5 and 6) to prevent an immediate second operation of the machine. In adding operations the shaft 40 is 65 rocked farther past normal position than in

total and sub-total operations. During adding operations it is necessary to release any depressed amount keys, as well as any of the control keys, whereas during total and sub-total operations no amount keys are depressed 75 and the shaft 40 is rocked a lesser distance than during adding operations.

Since the operations of the various parts have been described throughout the specification, it is not deemed necessary to describe 75 an operation of the mechanism.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a machine of the class described, the combination of a plurality of sets of depressible keys, a differentially adjustable element adapted to be adjusted to a plurality of positions, a flanged disk appropriate to each of said sets of keys and having notches in the flanges for normally permitting the operation of a key in each set, and means controlled by said differentially adjustable element for adjusting all of said disks, whereby only a key 85 in one set may be operated.

2. In a machine of the class described, the combination of a plurality of sets of depressible keys, a differentially adjustable element adapted to be adjusted to a plurality of positions, a flanged disk appropriate to each of said sets of keys, and having notches in the flanges for normally permitting the operation of a key in each set, a bar connecting all of said disks, and means controlled by said differentially adjustable element and attached to said bar for moving all of said disks according to the adjustment of the adjustable element whereby, keys of a certain group will 100 105 110 be operative according to the position of the adjustable element.

3. In a machine of the class described, the combination of a plurality of sets of depressible keys, a differentially adjustable element adapted to be adjusted to a plurality of positions, and a pivoted frame controlled by the said differentially adjustable element and common to all of said sets of keys for selecting any one or all of said sets of keys for 115 120 operation.

4. In a machine of the class described, the combination of a plurality of sets of control keys, a main operating device, means normally preventing the operation of said main operating device, connections requiring an operation of a key of each set for disabling said preventing means, a differentially adjustable element, and means controlled by said element for selecting any one of said sets of 125 130

keys for operation, and thereby disabling said connections for all except the selected set of keys, whereby said preventing means may be disabled by an operation of a key of the selected set.

5. In a machine of the class described, the combination of a plurality of sets of control keys, a main operating device, means normally effective to prevent an operation of 10 said main operating device, connections, intermediate said sets of controlling keys and said preventing means, requiring an operation of a key in each set to disable said preventing means, a differentially adjustable 15 element, adjustable to a plurality of positions, and connections controlled by said element for rendering the depression of a key in each set unnecessary, and determining, by its position, which set of keys will control 20 said preventing means.

6. In a machine of the class described, the combination of a plurality of sets of depressible keys of different classes, a differentially adjustable element having a normal position common to all of said classes, and a plurality 25 of positions of adjustment each appropriate to one of said classes, and a pivoted frame controlled by said differentially adjustable element and common to all of said 30 sets of keys for selecting any one or all of said classes of keys for operation.

7. In a machine of the class described, the combination with a plurality of sets of depressible keys of different classes, a differentially adjustable element having a normal position appropriate to all of the classes of 35 sets of keys, and positions of adjustment each appropriate to one of said classes, and a pivoted frame controlled by said element and 40 common to all of said sets of keys, whereby a key in each set may be operated when said frame is in its normal position, but only one of said sets of keys may be operated when the frame is out of its normal position, determined by the position of the element.

8. In a machine of the class described, the combination of a plurality of banks of control keys, a plurality of arms, one for each bank, and adapted to be rocked by the depression 50 of one of the keys in its appropriate bank, and a yoke member having a plurality of notches cooperating with said arms to permit a key in only one of said control banks to be depressed at a time.

55. 9. The combination of a plurality of control banks of keys; a rockable member, including a segment member and a plurality of flanged projections having a plurality of notches, said projections and notches cooperating with the banks of keys to selectively lock out the keys in certain banks, and permit the keys in another bank to be operated; and differentially movable means, including a 60 segment member cooperating with the first- 65

mentioned segment member to control the rockable member to select the desired bank of keys.

In testimony whereof I affix my signature.

FREDERICK L. FULLER.
